UNITED STATES PATENT OFFICE.

EUGEN HAGENBUCHER, OF ESSEN, GERMANY, ASSIGNOR TO FRIED. KRUPP AKTIEN-
GESELLSCHAFT, OF ESSEN-ON-THE-RUHR, GERMANY.

DESUPERHEATER.

Application filed February 8, 1924, Serial No. 691,524, and in Germany March 1, 1923.

This invention relates to a desuperheater to be used in connection with a surface condenser for steam power plants operating with superheated steam which undergo a large change in load during operation. In such condensing plants at times the exhaust steam of the power machines enters the condenser in still superheated condition, so that a part of the cooling surfaces of the condenser must be used to cool the steam down to its saturation temperature. This part of the cooling surfaces is therefore withdrawn from its normal function. The heat exchange between the cooling surfaces and the superheated steam proceeds only slowly under the low pressures prevailing in the condenser, so that in spite of the large difference in temperature between the superheated steam and the cooling water as compared with saturated steam, a relatively large cooling surface is required for cooling the steam down to its saturation temperature.

The purpose of the present invention is to eliminate this disadvantage by means of a particular apparatus in a simple manner.

In the drawing one example of the subject matter of the invention is somewhat diagrammatically shown in vertical section.

The surface condenser *b* is connected in the customary manner to the exhaust conduit *a* which opens into a receiving chamber *b*² of the condenser *b*. In the receiving chamber *b*² an open container *K* is arranged which holds porous bodies of large surface kept continually wet by suitable means such as the water supply pipe *L*, with which the steam comes in contact. The superheated steam coming to the condenser through the conduit *a* evap-

orates in the receiving chamber *b*² enough water to change it to saturated steam. Thereupon it is condensed in the condenser *b*. While there is now in the condenser a quantity of steam to be condensed increased by the amount of evaporated water, the cooling surface necessary is, on account of the relatively high co-efficient of heat exchange of the steam to be condensed, considerably less than the cooling surface which is necessary in order to bring the superheated steam without injected water to saturation.

The further operation of the condenser and the condensate conduit will need no explanation.

The chamber *b*² can be placed in the exhaust conduit immediately behind the point at which work is performed by the steam without changing the invention. In each case fresh water can always be used for saturating the steam because the impurities separated out of the water do not pass into the condenser.

I claim—

In a steam power plant operated with superheated steam under greatly varying loads, a condenser to which superheated steam is intermittently delivered from the power plant, and means for saturating the steam prior to its reaching the condenser, said means comprising a wet porous substance situated in advance of the condenser and with which the steam is passed in contact, said porous substance being adapted to give up moisture to the steam.

The foregoing specification signed at Essen, Germany, this 17th day of January, 1924.

EUGEN HAGENBUCHER.
